UNITED STATES PATENT OFFICE.

IRA LEWIS CONKLING, OF PHILADELPHIA, PENNSYLVANIA.

CIGARETTE-MAKING DEVICE.

No. 873,350.

Specification of Letters Patent.

Patented Dec. 10, 1907.

Application filed July 3, 1907. Serial No. 381,959.

To all whom it may concern:

Be it known that I, IRA LEWIS CONKLING, a citizen of the United States, residing at Philadelphia, in the county of Philadelphia and State of Pennsylvania, have invented a new and useful Improvement in Cigarette-Making Devices, of which the following is a specification.

My invention relates to an improvement 10 in cigarette-making devices of the variety adapted to be conveniently carried in the pocket, and my primary object is to provide a simple construction of such a device, which will be reliable in operation.

Referring to the accompanying drawing— 15 Figure 1 shows by a view in sectional elevation a cigarette-making device embodying my invention, the removable parts being shown in their relative positions for assembling. Fig. 2 is an enlarged broken view of the same in sectional elevation, showing by full lines the parts of the device when assembled preparatory to making a cigarette, and by dotted lines one of the positions assumed by the withdrawable tubes during the 20 making of a cigarette; and Fig. 3, a similar view of the outermost tube containing a cigarette formed therein and partially ejected, the cigarette being shown partly in section.

The receptacle for the tobacco and casing for the operative parts, which is represented at 4, is preferably formed of sheet-metal, though any other suitable material may be used, the metal of the ends 5 and 6 overlapping the top, bottom and sides of the casing, as shown, and the end 5 being provided with a hinged cover 7 through which to supply tobacco to the receptacle. In the casing and 35 extending along its bottom, but shorter than the latter, and fastened at one end in an opening in the casing-end 5 and near its opposite end to the casing-bottom, by a screw 8, is a stationary tube 9. In this tube is a stationary tube 10 projecting beyond the outer end of the tube 9 and concentric therewith, the inner end of the tube 10 being expanded, as represented at 11, to fit the tube 9 and close the inner end of the latter. Secured in 40 the tube 9 near its outer end is a band 12 carrying curved leaf springs 13 which preferably protrude beyond the tube 9. Journaled in the casing-end 6 and extending through the tube 9, is a conveyer 14. The form of the 45 conveyer which I prefer to employ is that illustrated, comprising a head 15 provided

with a shank 16 at which it is journaled in the casing-end 6; a knurled knob 17 screwed on the shank 16 to extend beyond the casing and by which to turn the head 15; and a spiral 18 formed of wire and fitting the tube throughout its length and fastened at its inner end to the head.

At 19 is represented the cigarette-paper-carrying tube of an internal diameter permitting it to be slipped over the tube 10 to envelop it and be readily removable therefrom, an annular bead 20 and groove 20' being provided on the inner and outer surfaces, respectively, of the tube 19 near its outer end, the bead serving as a stop, and the groove as a finger-grip for separating the tubes. This tube contains near its inner end an inwardly projecting spring 21, preferably formed by cutting two longitudinal slits in the edge of the tube and bending the tongue 21, so formed, inwardly, as shown in Fig. 1. Another tube 23 of slightly larger diameter than the tube 19 and of about the same length may be provided, for a purpose hereinafter stated. This tube contains near its outer end a manually operated plunger 24 confined in the tube by a pin 25 passing through it and slidably retained in guide-slots 26 in the tube.

The operation of the above-described preferred embodiment of my invention is as follows: A sheet of cigarette paper 27 is first wound about the tube 19 to project at one extremity beyond its outer end and the free overlapping edges of the paper are then secured together, as by moistening them to cause adhesion, and the projecting extremity of the paper is thereupon folded over the outer end of the tube, as represented at 28. The tube 19, with the paper in position on it, is then inserted into the tube 23 to cause the plunger 24 to bear against the folded end of the paper and securely confine the latter between the plunger and the end of the tube 19. The tubes 19 and 23 in their assembled condition with the paper 27 between them, are then slipped over the innermost tube 10, between the latter and the springs 13, to the position represented in Fig. 2, in which the bead 20 abuts against the outer end of the tube 10, the spring 21 bears against the outer surface of the last-named tube, and the springs 13 press against the tube 23. Assuming the receptacle to contain tobacco, turning the spiral 18 by the handle 17 introduces tobacco into the tube 10 against the

inner end of the plunger 24 and the folded end 28 of the paper. Continued turning packs the tobacco against the plunger 24 and the folded end of the paper with the 5 result of filling the tube of paper with tobacco and forcing the paper and tube 23, the latter against the resistance of the springs 13, off the tube 19, as the filling progresses. With the paper tube thus filled, as represented in Fig. 3, to remove the formed cigarette from the tube 23, the plunger 24 is pushed inward partially ejecting the cigarette from the tube, whereupon it may then be grasped by the fingers and fully withdrawn, and preliminary to the withdrawal the end of the cigarette may be twisted, as represented at 29 (Fig. 3). The springs 13, when the tube 23 is employed, serve to insure sufficient resistance against too ready 20 removal of the tube 23 during the filling operation; and the spring 21 is provided to prevent sliding of the tube 19 upon the tube 10 during this operation.

Employment of the tube 23, while desirable, especially under some conditions, as when the paper used is comparatively thin, is not necessary, and may be dispensed with. When thus omitted the cigarette is formed in the following manner: The paper is applied to the tube 19 and the latter slipped on the innermost tube 10, as above-described. In initially operating the conveyer to fill the paper tube a finger of the operator may be placed against the folded end of the 30 paper, until the tobacco has become sufficiently packed therein to form an abutment for the tobacco to press against, which, as the conveyer continues to operate, acts as a plunger filling the paper and forcing it as it 35 fills off the tube 10. When the tube 23 is omitted the springs 13 press against the paper between the latter and the tube for producing proper packing of the tobacco in the paper tube.

40 45 When the tube 23 is employed, it serves as a closure for the tube 10 to prevent accidental discharge of tobacco through it, when the device is not being operated.

What I claim as new, and desire to secure 50 by Letters Patent, is—

1. In a cigarette-making device, the combination of a receptacle for the tobacco, a stationary tube in said receptacle closed at its inner end and opening through said receptacle, a second stationary tube within said first-named tube concentric with it and open at both ends, means for forcing tobacco from said receptacle through said second tube, and a third tube about which to wrap a cigarette- 55 paper, adapted to be slipped over said second tube, with means for holding it thereon while the paper is being forced off said wrapped tube by the action of said forcing-means, for the purpose set forth.

2. In a cigarette-making device, the combination of a receptacle for the tobacco, a stationary tube on said receptacle, closed at its inner end and open at its opposite end, a second stationary tube in said first-named tube concentric with it and open at both ends, 60 means for forcing tobacco from said receptacle through said second tube, a third tube about which to wrap a cigarette-paper and adapted to be slipped over said second tube, and a spring interposed between said first-named and third tubes, for the purpose set forth.

3. In a cigarette-making device, the combination with a receptacle for the tobacco, a stationary tube on the receptacle, open to its 65 interior, and means for forcing tobacco from said receptacle through said tube, of a second stationary tube about which to wrap a cigarette-paper and adapted to be slipped over said second tube and held thereon while the 70 paper is being forced off said wrapped tube by the action of said forcing-means, and a third tube adapted to slip over said second tube and the paper thereon and provided with an abutment, for the purpose set forth.

4. In a cigarette-making device, the combination with a receptacle for the tobacco, having a stationary tube open to its interior, and means for forcing tobacco from said receptacle through said tube, of a second tube 75 about which to wrap a cigarette-paper and adapted to be slipped over said stationary tube and held thereon while the paper is being forced off said wrapped tube by the action of said forcing-means, and a third tube 100 adapted to slip over said wrapped tube and the paper thereon, and provided with a plunger, for the purpose set forth.

5. In a cigarette-making device, the combination of a receptacle for the tobacco, having a stationary tube within it, closed at its inner end and opening through said receptacle, a second stationary tube in said first-named tube open at both ends and expanded at its inner end to fit the interior of said first-named tube, a spiral-conveyer journaled at one end in a wall of the receptacle and equipped with means for turning it and extending into said second tube, a third tube about which to wrap a cigarette-paper and adapted to be slipped over said second tube and held thereon while the paper is being forced off said third tube by the action of said conveyer, a fourth tube adapted to slip over said third tube and the paper wrapped thereon and provided with a plunger near its outer end, and springs fastened on said first-named tube to bear against said fourth tube, for the purpose set forth.

IRA LEWIS CONKLING.
